MEASURING RULE DEVICE

William E. Evans, Waterbury, Conn., assignor to
Waterbury Lock & Specialty Company, Milford,
Conn., a corporation of Connecticut

Application September 26, 1936, Serial No. 102,647

1 Claim. (Cl. 33—138)

My invention relates to a new and improved measuring rule device.

One of the objects of my invention is to provide a measuring rule device of the type in which 5 a flexible tape is located within a case, so that the tape can be pulled out of said case, or pushed into said case.

Another object of my invention is to provide a device of this kind which shall be free from a 10 turnable drum or barrel on which the tape is wound and which will operate without the use of a spring or springs, for moving the tape back into the casing.

Another object of my invention is to provide a 15 device in which the tape is retained external to the case, after the tape has been partially pulled out of the case, without the use of manually operated brakes or detents.

Another object of my invention is to provide 20 a device having few and simple parts and which can be very cheaply constructed.

Other objects of my invention will be set forth 25 in the following description and drawing which illustrates a preferred embodiment thereof, it being understood that the above statement of the objects of my invention is intended to generally explain the same without limiting it in any manner.

Fig. 1 is a top plan view of the device, showing 30 the tape slightly protruding from the case. Part of the case is represented as being broken away in Fig. 1 in order to illustrate the interior construction of the device.

Fig. 2 is a sectional view on the line 2—2 of 35 Fig. 1.

Fig. 3 is a partial perspective view showing one 40 face of the case and also showing the inner end of the tape as it is introduced between the elements of the stationary mandrel member.

Fig. 4 is a perspective view showing the mandrel member which is affixed to the inner surface 45 of one of the parts or faces of the case.

Fig. 5 is a sectional view on the line 5—5 of 50 Fig. 2.

Fig. 6 shows the central tubular rivet-member 55 which connects the two parts of the case to each other.

Fig. 7 is a sectional view on the line 7—7 of 60 Fig. 3.

As shown in Fig. 2, the case 1 consists of two members 2 and 3 which are of substantially equal size and dimension. The edge portion 3a of the case member 3 overlaps the edge portion of the case member 2.

A tubular rivet-member 4 is used to connect 65 the two case members 2 and 3 to each other and also to connect the mandrel member 5 to the case member 2.

The construction of the rivet-member 4 is 70 shown in Fig. 6. Said rivet-member 4 has its

ends of identical contour. One end of said rivet-member 4 is provided with longitudinal slots 6 and 6a, and said slotted end is shaped so as to provide tongues 7 and 7a and four shoulders 8. The other end of said member 4 also has 5 tongues 7 and 7a and shoulders 8.

As shown in Figs. 4 and 5, the mandrel member 5 has a central opening 9. Said opening 9 is provided with parallel straight-line faces or walls 10 and with concave end faces 11. The walls 10 10 are longer than the chords of walls 11.

The opening 9 is formed by cutting out the metal of the mandrel 5.

In order to stiffen the walls of said opening 9, a central portion 12 of the base of the member 5 15 can be stamped inwardly so as to provide a shoulder 14 at the inner face of the base of the mandrel member 5.

A construction similar to that of the member 12 (including the opening 9) is provided in the end 20 wall of the case-member 2, and this is designated by the reference numeral 12a.

As shown in Fig. 2, the member 12a nests partially in the member 12 when the parts are assembled. With the exception of the inwardly 25 stamped part of member 12, the base of mandrel 5 abuts the adjacent planar face of case-member 2. The tongues 7 and 7a are bent outwardly so as to provide a rivet-like connection between the members 2, 3, and 5. The case-member 3 is 30 provided with an inwardly stamped central portion having an opening similar in shape to the opening 9, in order to permit the adjacent tongues 7 and 7a to be passed through said case-member 3.

Caps 15 and 15a have flanges which are spun 35 over the tongues 7 and 7a so that these caps are rigidly maintained in position. Said caps 15 and 15a fit frictionally or have a drive fit in the tubular member 4. This construction prevents any 40 turning of the mandrel member 5 relative to the case, because the member 5 is held with sufficient friction against the inner surface of the wall of the member 2.

The mandrel member 5 is provided with integral laterally projecting members 16 which may be substantially rigid and these projecting members 16 are provided with resilient tongues 16a which are bent inwardly of the imaginary cylinder whose base is the circular edge of the member 5. The parts of the device can be made of metal 50 or other suitable material.

The tape 17 is made of resilient and flexible 55 steel or other metal, and it has the concavo-convex cross section shown in Fig. 7. As shown in Fig. 3 the inner end 17a of the tape 17 can be introduced between the member 4 and the inner ends of the resilient tongues 16a. For this purpose the case is provided with a lateral slot 18. The outer end of tape 17 has an angular metal 60

tongue 16 connected to said tape by rivets 19a. The lateral projecting end of tongue 19 is of sufficient size so that it cannot enter the case. The rivets 19a can enter the case.

5 The inner end of the tape is guided resiliently by the members 16a so that it is automatically coiled around the axis of the member 4, the windings being held spaced at all times from the member 4 as shown in Fig. 2. The entering tongue or prong 16a which is directly aligned with the 10 opening of the case, and with which the rounded entering end of the tape first contacts, is shorter than the other prongs, the other prongs being of equal length.

15 The resilience of the tape is sufficient to maintain the inner portion of the tape in the form of a shell, said shell having a plurality of spiral turns, and the outer end of the tape is a continuation of the outermost winding or part of 20 said shell:

The resilient tongues 16a can bend in a direction away from the central axis of the tube 4, as the thickness of said shell increases, although this bending movement is not necessary. Said 25 tongues 16a act as resilient braking members, which automatically hold the tape in its adjusted position. Hence it requires a certain amount of manual force either to pull the tape out of the case or to push the tape into the case and the 30 tape has sufficient stiffness to enable the same to be pushed into the case.

The tape has sufficient resilience and flexibility 35 so that it can be bent into the form of the shell which is illustrated in Fig. 2. The flexibility of the tape permits it to straighten in said shell, from the concavo-convex cross-section illustrated in Fig. 7, to a cross-section having straight-line elements.

40 The inner end of the tape has an inwardly bent and rounded end-portion 17a. This is an important feature of the invention as otherwise the tape could not be properly introduced into the casing between the tongues or prongs. The tape may have an end which has an inherent 45 flexing tendency to form the rounded tip 17a, even though said tip may be straightened by finger pressure. This rounded tip or flexing can be formed by a suitable tool. I do not wish to be limited to the use of said rounded tip, as 50 other constructions would enable the end of the tape to bend in the form of an arc, so that the tape could be spirally wound.

55 When the tape is pulled out of the shell, its natural stiffness is sufficient to maintain the tape substantially straight, if the tape is held with its convex side downwards.

The tape bends from this straight-line shape only when about fifty inches of the tape have been pulled out of the case.

60 When the tape is held with its concave side downward, it is quite flexible and it begins to bend when about sixteen inches of the tape had been pulled out of the case.

The drawing is substantially to scale and it 65 can be seen that the diameter of the case is about three inches. Hence the resilience of the tape is sufficient to cause it to wind up within the case, in the form of a spiral, whose outer wall abuts the effective inner wall-portion of the case. That is, the inner surfaces of members 70 16 and 16a constitute a portion of the effective lateral wall of the case. These members 16 and

16a may be defined as forming the tape-confining wall of the case.

Referring to Fig. 3, when the inner end of the tape is pushed inwardly, the natural resilience and contour of the tape causes its convex face to slide in contact with the tips of the resilient tongues 16a, until the inwardly bent end 17a of the tape comes into contact with another part of the tape. The rounded end 17a causes the tape to form the first turn or winding and the 10 tape has sufficient stiffness to enable the same to be pushed further inwardly, thus forming additional turns. The natural resilience of the tape maintains the respective turns thereof in tight contact with each other and outward pressure is maintained upon the tongues 16a, which 15 may bend outwardly as the result of said pressure. Said pressure is sufficient to substantially straighten the lateral elements of the tape from the concavo-convex shape shown in Fig. 3, to a 20 straight-line shape.

The fact that the tongues 16a retain the tape within the case so that it requires a certain pull to withdraw the tape from the case, is a valuable feature of the invention as there is no danger of the tape shooting out suddenly as in prior devices in which the coil tape provided a spring force which projected the tape outwardly with considerable velocity, when a detent was released.

25 While I prefer to use the member 5 having 30 tongues 16a which are separate from the wall of the case proper, I do not wish to be limited to this feature as the tongues 16a may be considered as forming part of the effective inner 35 wall of the case.

In order to define the structure more clearly in the claim, and considering Fig. 4, the ends of the tongues 16a which are directly adjacent the projections 16, may be designated as the outer ends of said tongues 16a. An imaginary 40 circumscribing cylinder may be considered as corresponding generally to the projections 16. The tongues 16a are therefore bent inwardly relative to said circumscribing cylinder.

I have shown a preferred embodiment of my 45 invention, but it is clear that numerous changes and omissions can be made without departing from its spirit.

I claim:

A measuring-rule device comprising a case of 50 general cylindrical contour, said case having an opening in the lateral wall thereof through which a tape can be inserted, the end walls of said case also having aligned openings substantially centrally located therein, each of said openings having opposed concave walls and intermediate 55 straight-line walls, said openings being located in inwardly stamped portions of said end walls, a mandrel member having a base provided with an inwardly stamped portion having an opening 60 of the aforesaid contour, the inwardly stamped portion of one of said walls being nested within the inwardly stamped portion of said base, a hollow rivet member of general cylindrical form 65 having tongues of concavo-convex cross section, said tongues being bent outwardly and over the concave walls of the openings of said base and of said end walls, said base having inwardly directed projections having tongues which are bent inwardly relative to a circumscribing cylinder 70 which corresponds to the contour of said base.

WILLIAM E. EVANS.
